Primary Examiner — David Muller**CLAIM**

The ornamental design for an eyewash device, as shown and described.

DESCRIPTION

FIG. 1 is an isometric view of a front side of the eyewash device;

FIG. 2 is an isometric view of a back side thereof;

FIG. 3 is a side view of a right side thereof;

FIG. 4 is a front view thereof;

FIG. 5 is a side view of a left side thereof;

FIG. 6 is a back view thereof;

FIG. 7 is a top view thereof; and,

FIG. 8 is a bottom view thereof.

The broken line showing of parts of the drawings is included for the purposes of illustrating use and environment and forms no part of the claimed design.
